UNITED STATES PATENT OFFICE.

ARTHUR A. PAGE, OF RACINE, WISCONSIN.

MECHANICAL-PENCIL ERASER.

Application filed November 6, 1925. Serial No. 67,362.

This invention relates to improvements in mechanical pencils, and more particularly to a mechanical pencil having an adjustable and replaceable eraser.

5 Many mechanical pencils now in use are not equipped with erasers, or mechanical pencils, as well as other pencils, are provided with cupped portions at the end in which the eraser is held. The exposed portion of the 10 eraser quickly becomes worn down with the result that the pencil is discarded or the user is subjected to the inconvenience of using the same without an erasing portion.

It is, therefore, the principal object of the 15 present invention to overcome the above objections by providing a pencil in which the eraser carrying portion and eraser may be adjusted with respect to each other to expose more or less of the eraser as it becomes worn.

20 A further object of the invention is to provide a pencil of the class described in which the length of the pencil remains constant and does not vary with different adjustments of the eraser.

25 A further object of the invention is to provide a pencil of the class described in which the eraser may be readily removed and replaced when desired.

30 A further object of the invention is to provide an adjustable eraser end for pencils adaptable to any form of pencil, and particularly to the so-called self feeding or mechanical pencils.

35 A further object of the invention is to provide an eraser and pencil of the class described which is of very simple construction, is inexpensive to manufacture, is strong and durable, and is well adapted for the purposes described.

40 With the above and other objects in view the invention consists of the improved pencil and eraser attachment and its parts and combinations as set forth in the claim and all equivalents thereof.

45 In the accompanying drawing in which the same reference characters indicate the same parts in all of the views:

Fig. 1 is a side view of a pencil having the improved adjustable eraser attachment;

50 Fig. 2 is a longitudinal sectional view thereof;

Fig. 3 is a cross sectional view taken on line 3—3 of Fig. 2 and on a larger scale; and

Fig. 4 is an enlarged vertical sectional view of the upper portion of the pencil. 55

Referring now more particularly to the drawing it will appear that the numeral 5 indicates a mechanical pencil of ordinary construction, the body portion of which is tubular to receive the mechanical lead feeding mechanism 6. The upper end of the body portion is open and is internally threaded to receive a plug 7 formed with an enlarged head, the plug having a longitudinally extending rectangular opening 8 through which 65 the shank 9 of a plunger 10 slidably extends.

As shown, the head of the plug 7 rests against the end portion of the tubular body and is enclosed by a revoluble barrel or cylinder member 11 which is slightly resilient 70 and which has a loose engagement with the head of said plug and is retained thereon by rib and groove means 12, the member 11 being free to turn on the plug head.

The major portion of the cylinder member 11 is internally threaded as at 13 to move the member 10, the head portion of which is externally threaded to engage the threads 13. A cylindrically shaped eraser member 14 seats on said member 10 so as to be moved 80 thereby, and in proper adjustment the end portion of the eraser will project beyond the outer end portion of the member 11 to be exposed, the outer end portion of the cylinder member 11 being tapered inwardly to bind 85 the eraser.

In use, as the end portion of the eraser becomes worn, the cylinder member can be turned to move the plunger member 10 upwardly therein, thereby raising the eraser to 90 expose more of its end portion. Adjustments of this character will not vary the length of the pencil. Also when necessary the eraser member may be readily replaced and both the cylinder member and plug 7 are removable to permit access to the interior of the pencil body. 95

From the foregoing description it will be seen that the improved pencil and eraser attachment is of very simple and novel construction, and is well adapted for the purpose set forth. 100

What I claim as my invention is:

In a pencil, a body portion, a plug threaded into the end portion thereof, a cylinder member revolubly engaging the exterior of said 105

plug and having a detachable engagement therewith and extending outwardly therefrom, said cylinder member being internally threaded, a plunger member having a squared shank and a threaded head portion directly carried and engaged by said shank portion, said shank portion extending through said plug and said head portion being enclosed

within the cylinder member and in threaded engagement therewith, and an eraser with 10 in said cylinder member and supported and moved by the head portion of said plunger member.

In testimony whereof, I affix my signature.

ARTHUR A. PAGE.
